US0D1062219S

(12) **United States Design Patent** (10) **Patent No.:** **US D1,062,219 S**
(45) **Date of Patent:** **** Feb. 18, 2025**

(54) **TOTE BAG**

(71) Applicant: **Qiao Liu**, Foshan (CN)

(72) Inventor: **Qiao Liu**, Foshan (CN)

(**) Term: **15 Years**

(21) Appl. No.: **29/954,467**

(22) Filed: **Jul. 26, 2024**

(30) **Foreign Application Priority Data**

Jul. 19, 2024 (CN) 202430452888.7

(51) **LOC (15) Cl.** **03-01**

(52) **U.S. Cl.**

USPC **D3/246**; D3/245
